UNITED STATES PATENT OFFICE.

HANS HEID, OF BERLIN-SUDENDE, GERMANY, ASSIGNOR TO NORDDEUTSCHE KUHLER-FABRIK A-G, OF BERLIN-TEMPELHOF, GERMANY.

FUEL-FEEDING SYSTEM FOR CARBURETORS.

Application filed June 28, 1922. Serial No. 571,538.

To all whom it may concern:

Be it known that I, HANS HEID, a citizen of Germany, residing at Berlin-Sudende, Germany, have invented certain new and useful Improvements in Fuel-Feeding Systems for Carburetors; and I do hereby declare the following to be a full, clear, and exact description of the invention, such as will enable others skilled in the art to which it appertains to make and use the same.

The invention relates to new and useful improvements in fuel feeding systems for carburetors, and more particularly to that class wherein the pressure of the exhaust gases acts on the fuel in a tank below the carburetor, to lift it into an auxiliary vessel of relatively small capacity, wherefrom the fuel may be fed by its own gravity to the carburetor.

It is the object of my invention to devise a system of the above class which shall be reliable in its operation, simple in its construction and whereby the fuel will give a better effect than with the known systems.

It is an important feature of the invention that the common spring controlled valve allowing the exhaust gases to pass to the main tank is arranged on the auxiliary vessel. The exhaust gases give off their heat to the auxiliary vessel and its contents before reaching the reducing valve which therefore remains cool. Heretofore this valve has been arranged on the exhaust manifold and its spring has become deteriorated by the heat of the gases after a comparatively short time.

Further objects and advantages of the invention will be apparent in reading the specification and from examination of the drawings, forming part of the present application for Letters Patent.

The invention is illustrated in the accompanying drawings, in which—

Fig. 1 illustrates my improved system diagrammatically in connection with an auxiliary vessel, shown in Figs. 3 and 4.

Fig. 2 shows an embodiment of my invention with an auxiliary vessel constantly open to the atmosphere; a modified construction with an auxiliary vessel normally closed to the atmosphere is illustrated in Figs. 3 and 4 in two different sections turned to each other about 90°. Fig. 3 showing the exit of the gases and Fig. 4 the entrance of the

gases and of the fuel. Fig. 5 shows a modi-

fied air-valve provided with snapping springs.

Referring to Fig. 2 of the drawings *a* designates the auxiliary vessel, *c* the fuel supply pipe connected to the main tank 5 arranged in the well known manner in the automobile-frame below the level of the carburetor and *d* the pipe leading to the carburetor. The cover *b* of the vessel *a* has a central part *j* carrying the dependent pipes *h*, *f* enclosed by the pipe *y* suitably fastened by the screwed plug *e*. The part *y* with the pipes *h*, *f* can be easily removed.

According to the present invention the exhaust gases for producing the pressure in the main tank 5 are led through the said pipes of the auxiliary vessel. They pass through a branch pipe *c'* of the exhaust manifold 2 of the motor 1 and enter through the plug *e* into the pipe *y*. The pipe *f* is closed at its lower end and is perforated in its upper part, while the pipe *h* is open at its lower end and closed at its upper end by the pressure reducing valve *g*. The gases are therefore forced to pass in zigzag through the pipes to the valve *g* thereby giving off their heat to the fuel contained in the vessel *a* and depositing their carbon and their other impurities in the pipes. The pressure reducing valve *g* is combined with the relief valve *z* both being held on their seats by the springs 3, 4. The cool and clean gases do not impair the operation of these springs as heretofore experienced with the hot, uncleaned gases. The pipe *i* leads the gases to the main tank 5, wherein they press upon the surface of the fuel. Owing to this pressure the fuel is fed through the pipe *x* and the valve *k* into the vessel *a*. The valve *k* is controlled by the float *l* through the medium of the two-armed lever *m*. When sufficient fuel has been accumulated in the vessel *a* the float *l* closes the valve *k*. The fuel pressed upwards in the pipe *x* helps to keep the valve *k* closed on its seat. The vessel *a* is open through the vent *n* to the atmosphere so that the fuel is fed by its own gravity from the vessel *a* through the pipe *d* to the carburetor 6. The inlet of the gases and the outlet of the fuel are arranged in close proximity in the bottom of the vessel in order that the fuel may be effectively heated before passing to the carburetor.

In Figs. 3, 4 like numerals designate the like parts. The construction shown in this

instance is a more elaborate one and differs from the construction already described in the fact that the air vent *n* is normally closed by a valve which opens only when the motor 5 is at rest or in other instances when there is no pressure in the main tank. There is no float controlled valve for the inlet of the fuel.

The exhaust gases enter through the passage *e* into the chamber *o* and the pipe *y* enclosing the perforated pipes *h*, *f*. The gases cooled-off and cleaned in these pipes leaves through the pressure reducing valve *g* for the passage *i* to the main tank. The fuel 10 is lifted from the main tank through the connecting pipe *x* and the passage *c* into the vessel *a* and is fed through the plug *d* to the carburetor. The passage *c* has a depending prolongation *v* for the purpose herein- 15 after described. For the air-vent *n* there is provided the float valve *t* arranged in the guide-tube *s* and supported in its lowest position by the cross pin *s'*.

Assuming the float valve *s* be in its lowest 20 position or in any other position uncovering the air vent *n*, the fuel contained in the vessel *a* is fed by its own gravity through the plug *d* to the carburetor. These conditions exist in starting the engine or in other instances when there is no pressure in the main 25 tank to lift the fuel into the auxiliary vessel and the level of the fuel in the vessel is not high enough to keep the valve *t* closed.

When after starting owing to the restored 30 pressure in the main tank the level of the fuel in the vessel *a* raises the valve *t* closes the vent *n* which then remains under normal running conditions in closed position. The air inclosed at the top of the vessel *a* forms 35 an elastic bolster between the fuel contained in the vessel and the fuel tends to rush in into the vessel through the passage *c*. When fuel is delivered to the carburetor the air bolster expands and allows fresh fuel to 40 come in from the main tank. When on the other hand the pressure of the gases in the main tank ceases it is desirable to again uncover the vent *n* in order to allow of a gravity feed for the next starting of the machine.

45 While this is attained without further means owing to the contraction of the gases and to their escape through the passage *c* I prefer to provide the prolongation *v* of the passage *c* which dips under the normal level of 50 the fuel in the vessel *a*. When the pressure in the main tank ceases the fluid column in the pipe surges back through the prolongation *v* a quantity of fuel sufficient to cause the valve *t* to uncover the vent *n*. By this 55 means the system is enabled to feed the fuel by its own gravity to the carburetor at every starting of the engine, notwithstanding the vessel being normally closed to the atmosphere.

60 65 The normally closed vessel has an ad-

vantage as against the open vessel as it feeds the fuel to the carburetor even in the case the latter being on the same or on a higher level as the vessel. This happens often in hill-climbing when the automobile assumes a 70 very steep position.

In Fig. 5 we see an air-valve *t'* which is for the sake of better guidance and of interchangeability separated from its float *t''*. To keep the valve *t'* closed notwithstanding the 75 continued small movements of the float we may provide snap springs 10 or the like means known in the art which are overcome only when the float moves into its extreme 80 positions.

As shown by the drawing, the central heating and cleaning pipes as well as the valves are easily removable for cleaning and exchanging. Preferably they are all arranged 85 on and combined with the cover *b* of the vessel *a*. The cover *b* is fastened to the vessel *a* by the screws *q*. A strainer *p* is held with its upper border between the cover *b* and the border of the vessel *a* projects down into the vessel and surrounds the heating 90 pipes and the float valve *t* so as to afford a great area to the passing fuel.

What I claim is:

1. In a fuel feeding system a carburetor, a main tank, an auxiliary vessel located at 95 a higher elevation than the main tank, ducts connecting said vessel with the main tank and with the carburetor, a pipe within said vessel, a duct connecting said pipe with the exhaust manifold of an internal combustion engine, and a second duct connecting said pipe with said main fuel tank, whereby the exhaust gases from the engine are caused to pass from the manifold to said pipe and thence to the main tank.

2. In a fuel feeding system a carburetor, a main tank, an auxiliary vessel located at 100 a higher elevation than the main tank, ducts connecting said vessel with the main tank and with the carburetor, a pipe within said vessel, a duct connecting said pipe with the exhaust manifold of an internal combustion engine, a second duct connecting said pipe with said main fuel tank, whereby the exhaust gases from the engine are caused to pass from the manifold to said pipe and thence to the main tank, and a pressure reducing valve arranged in said pipe.

3. In a fuel feeding system a carburetor, a main tank, an auxiliary vessel located at 110 a higher elevation than the main tank, ducts connecting said vessel with the main tank and with the carburetor, a pipe within said vessel, a duct connecting said pipe with the exhaust manifold of an internal combustion 115 engine, a second duct connecting said pipe with said main fuel tank, whereby the exhaust gases from the engine are caused to pass from the manifold to said pipe and thence to the main tank, and means ar- 120

125

130

ranged in the pipe for cleaning the said gases.

4. In a fuel feeding system a carburetor, a main tank, an auxiliary vessel located at 5 a higher elevation than the main tank, ducts connecting said vessel with the main tank and with the carburetor, a pipe within said vessel, a duct connecting said pipe with the exhaust manifold of an internal combustion engine, a second duct connecting 10 said pipe with said main fuel tank, where-

by the exhaust gases from the engine are caused to pass from the manifold to said pipe and thence to the main tank, and a float controlled valve in the duct connecting 15 the vessel with the main tank.

In testimony whereof I affix my signature.

HANS HEID.
